UNITED STATES PATENT OFFICE.

ERASTUS WOODWARD, OF BOSTON, ASSIGNOR TO GEORGE W. COPELAND,
TRUSTEE, OF MALDEN, MASSACHUSETTS.

BOOT AND SHOE SEWING MACHINE.

SPECIFICATION forming part of Letters Patent No. 234,513, dated November 16, 1880.

Application filed June 29, 1880. (Model.)

To all whom it may concern:

Be it known that I, ERASTUS WOODWARD, of Boston, in the county of Suffolk and Commonwealth of Massachusetts, have invented 5 an Improvement in Boot and Shoe Sewing-Machines, of which the following is a specification.

This invention is an improvement upon that described in reissue Letters Patent No. 6,535, 10 dated July 6, 1875, granted Gordon McKay and Robert H. Mathies, assignors to Gordon McKay, trustee.

It consists in the combination of the horn with a whirl having alternate periods of rotation and rest as it is moved in one direction; 15 also in mechanism for providing the whirl with said movement.

The operation and construction of the horn and whirl are fully described in said Letters 20 Patent, and also in Letters Patent No. 45,422, granted McKay and Blake, December 13, 1864, and in various patents of subsequent date.

The mechanism in the horn for operating the whirl is the same mechanism that is described in the said reissue Letters Patent No. 25 6,535.

Reference is made to the accompanying drawings, forming a part of this specification, in explaining the nature of my invention, in 30 which—

Figure 1 is a view, part in elevation and part in section, of my invention. Fig. 2 is a plan below the line $x-x$ of Fig. 1. Fig. 3 is a side elevation of my improvement. Fig. 4 is 35 a cross-section on the line $y-y$ of Fig. 1, showing one position of the operative mechanism hereinafter described. Fig. 5 is a cross-section on the same line, showing another position thereof.

The whirls have been provided with alternate periods of rotation and rest for the purpose of feeding the thread to the hook-needles, as described in said reissue Letters Patent—that is, the whirl has been made to turn around 40 the needle about two-thirds of a revolution at a time, when the needle has arrived at the lowest part of its stroke, carrying and laying the thread into the hook of the needle, and then, when the needle is withdrawn from the 45 whirl, to return or turn back to its first posi-

tion, ready to again perform the operation of laying the thread into the hook of the needle.

Instead of providing the whirl with alternate periods of rotation and rest, in which the movement of the whirl is reversed between the 55 rests, I provide the whirl with a movement of rotation in one direction, and provide one period of rest for each complete revolution.

A represents the horn; B, the work-plate bed or support; C, the whirl; c, a bevel-gear 60 upon the whirl; c', a bevel-gear upon the shaft D; d, the bevel-gear at the lower end of said shaft; e, the bevel-gear upon the horizontal shaft E, which engages with the bevel-gear d; e', a bevel-gear upon the said shaft E, which 65 engages with the bevel-gear f, upon the vertical shaft F. Thus far, the construction is similar to that described in the said reissue Letters Patent.

The shaft F has a bearing in the foot of the 70 horn, and is operated by means of the cam-groove G in the block g, and cam-pin H upon the cam-disk h. The shaft F projects upward from the central block, g, and furnishes the upper bearing thereof. Suitable bearing at 75 the lower end of the block in the frame a' is also provided.

The cam-disk h is revolved continuously by means of the shaft h', connected by the bevel-gear h² h³ and shaft h⁴, or in any other desirable manner, with the main shaft of the 80 machine.

The block g is further provided with the lugs g², which are separated by a space, g³, a trifle greater than the width of the cam-disk h. 85

The lugs are so arranged upon the block as to bring the space between them in line with the upper portion of the cam-groove G. The cam-disk h is cut away at h⁵, leaving the boss h⁶ supporting the cam-pins H, and the shoulders h⁷. 90

Upon the revolution of the cam-disk the cam-pin H enters the cam-groove G at its lowest point and revolves the block g, leaving the cam-groove at the upper end of the block. 95 At the instant immediately preceding its disengagement from the groove the cam-disk commences to enter the recess between the lug g² at the point h⁷, and the edge of the cam-disk between the shoulders h⁷ acts in connec- 100

tion with the lugs g^2 in maintaining the block at rest until the cam-pin is about entering the lower portion of the cam-groove G, when the shoulder h^7 passes beyond the lugs g^2 and allows the block to be revolved.

The ratio of the rest to the movement of the block g , as shown by the drawings, is about three to one, providing the cam-disk h has a uniform rate of speed at all times.

10 By providing the blocks g with two cam-grooves and the disk h with two cam-pins, and in otherwise modifying the shape of the cam-disk, the block g may be rotated twice in one revolution of the cam-disk h , and other modifications of its movement are obvious.

15 It will be observed that the space between the shoulders h^7 and the boss h^6 provides sufficient room for the rotation of the lugs g^2 between them immediately after the commencement and before the end of the rotation of the block g ; also, that the portion h^8 of the cam-disk, in connection with the lugs g^2 , act as stops in holding the block g stationary until the cam-pin has reached a position to engage with the cam-groove; also, that the construction and arrangement of the cam-disks, cam-pins, lugs, and cam-groove are such that the cam-pin must have entered, or must be about to enter, the cam-groove before the portion h^8 of the cam-disk has revolved beyond the lugs g^2 ; also, that the cam-pin must be about leaving the cam-groove when the portion h^8 of the cam enters between the lugs.

20 It is desirable that the block be brought to rest by the cam-pin, in which case, of course, the portion of the cam-groove at the lower and upper ends must be substantially vertical. This construction is desirable in order that the lugs g^2 may not backlash on the portion h^8 of the cam-disk after the cam-pin H leaves the groove.

25 The advantages of this invention consist mainly in the economy and simplicity of construction.

30 40 45 In operation, the whirl C is revolved once for every revolution of the block g , and then rests until it is again revolved by the cam-pin H and block G , the whirl making one complete revolution, then resting about twice the

time in which the revolution was made, and then again making a revolution.

Having thus fully described the invention, what I claim, and desire to secure by Letters Patent, is—

1. The combination, with the supporting-horn and whirl C mounted therein, of the block g , provided with the cam-groove G, and the lugs g^2 , the cam-disk h , provided with the cam-pin H and projecting portion h^8 , and mechanism for operating said disk and communicating the proper motion from said block g to the whirl, substantially as described.

2. The combination, with the supporting-horn and whirl C mounted therein, of the block g , provided with the cam-groove G, the cam-disk h , provided with the cam-pin H and projecting portion h^8 , and mechanism for rotating the disk h , and for communicating the proper rotary motion from the block g to the whirl, and for holding the block stationary during a portion of the rotation of said disk, whereby the whirl is caused to have alternate periods of rotation and rest, substantially as described.

3. The combination, with the supporting-horn and whirl mounted therein, of the block g , provided with the cam-groove G, the disk h , provided with the cam-pin H , and mechanism for rotating said disk, for communicating motion from the block g to the whirl and for locking the said block in a stationary position while the cam-pin H is not engaging the cam-groove G, substantially as described.

4. The combination, with the supporting-horn and whirl mounted therein, of the block g , provided with the spiral groove G, extending completely around the block and otherwise shaped, as described, mechanism for communicating motion from the block to the whirl, and a revolving disk provided with the cam-pin H , adapted to engage the cam-groove during a portion of its revolution in revolving the block g , and mechanism for revolving the cam-disk, all substantially as set forth.

ERASTUS WOODWARD.
